[57] **ABSTRACT**

In electromechanical apparatus, which includes a helical spring as a delay item for producing artificial reverberation, a movable element of a transducer is rigidly connected to at least one turn of the spring at a point intermediate the ends of the spring without interrupting its continuity. The movable element is a rotatable frame-wound coil and the connection is made between the spring and the sides of the coil disposed in parallel relationship with its axis of rotation. The portions of the turn or turns of the spring connected to the movable element are deformed inwardly toward the coil.

ELECTROMECHANICAL APPARATUS FOR PRODUCING ARTIFICIAL REVERBERATION

SUMMARY OF THE INVENTION

The present invention is directed to electromechanical apparatus including a helical spring which acts as a delay element for producing artificial reverberation and, more particularly, it is directed to the use of electromechanical transducers including a movable element rigidly connected to the spring at the point intermediate the ends of the spring. The transducers apply mechanical vibrations to the spring and pick up the vibrations transmitting by the spring.

In a conventional form of electromechanical apparatus for producing artificial reverberation, an electromechanical transducer is disposed at each end of the helical spring. In a more recent form of such apparatus, at least one transducer, usually the pickup transducer, is not disposed at an end of the helical spring but is located intermediate the ends of the spring. In this case the continuity of the spring is interrupted by a movable element, usually a rotatable frame-wound coil, of the transducer which is coupled to the spring. It is essential for reliable functioning of such a reverberation apparatus that no reflections, or only slight reflections, occur at the location at which the transducer is inserted, otherwise the desired "live" impression of the reverberation would be disturbed.

Moreover, a good transmission of high frequency vibrations necessitates that the coupling between spring and the transducer is as close as possible. It was hitherto not possible for these two requirements to be properly satisfied. In addition to substantial mechanical difficulties, there were also undesirable and troublesome reflections because interruption of the continuity of the helical spring, due to the introduction of the movable element of the transducer between the ends of the spring, resulted in the creation of a type of junction which disturbed the smooth flow of torsional vibrations traversing the spring.

Therefore, it is essential to insure that the insertion of a transducer intermediate the ends of the spring results in the least possible disturbance of the vibrations travelling through the spring. In particular, the degree of freedom of the individual modes of vibration must not be impaired by the introduction of the transducer, since this could, for example, convert the torsional vibrations into compressive vibrations. It is possible for transverse vibrations to occur in addition to torsional vibrations and compressive vibrations, such transverse vibrations being capable of producing disturbance effects in the same way as the compressive vibrations.

It is the primary object of the invention to provide an improved apparatus for producing artificial reverberation, in which the disadvantages of known apparatus are obviated or substantially reduced.

Accordingly, the present invention provides electromechanical apparatus for producing artificial reverberation, including a helical spring which functions as a delay element, and electromechanical transducers for applying mechanical vibrations to the spring and for picking up the vibrations transmitted by the spring. In this apparatus at least one of the transducers is coupled to the spring intermediate the ends of the spring by a movable element of the transducer which is rigidly connected to at least one turn of the spring without any interruption to the continuity of the spring at the connection.

Preferably, the movable element of the transducer coupled to the spring intermediate the ends of the spring is a rotatable frame-wound coil. Conveniently, a connection between at least one turn of the spring and the rotatable frame is made directly to a side of the frame which is parallel to the axis of rotation of the frame. The side of the frame may be arranged inside or outside the turn or turns to which it is connected. Advantageously, the connection is made by means of a hard, nonelastic adhesive.

In a preferred embodiment of the invention, each turn of the spring connected to the rotatable frame is deformed in-

wardly, so that the polar moment of inertia of the deformed turn plus the rotatable frame is at least approximately equal to that of turns not connected to the rotatable frame-wound coil.

To insure that the stiffness of each inwardly deformed turn of the spring plus frame is equal to the stiffness of the undeformed turns of the spring, it is furthermore preferable that each deformed spring turn should be provided with a reduced portion or notch which results in a corresponding reduction in its stiffness.

The various features of novelty which characterize the invention are pointed out with particularity in the claims annexed to and forming a part of this disclosure. For a better understanding of the invention, its operating advantages and specific objects attained by its uses, reference should be had to the accompanying drawing and descriptive matter in which there are illustrated preferred embodiments of the invention.

BRIEF DESCRIPTION OF THE DRAWING

20 In the drawing:

FIG. 1 is a diagrammatic illustration of a basic form of known reverberation apparatus; and

FIGS. 2, 3 and 4 are diagrammatic views of parts of three embodiments of the invention.

DETAILED DESCRIPTION OF THE INVENTION

In FIG. 1, a known reverberation apparatus is illustrated and is provided with a helical spring S which is subdivided into two portions S1 and S2. A rotatable frame-wound coil D2 of a pick up transducer is positioned between the two axially spaced helical spring portions S1 and S2 in the magnetic field of a magnet system M2 having poles PN2, PS2. An input transducer, having a rotatable frame-wound coil D1, is disposed between the poles PN1, PS1 of a magnet system M1, however, it is located at one end of the helical spring and the spring is supported at that end to the point A by the frame-wound coil D1 and a suspension F1, and it is supported at the other end to a fixed point B via the suspension F2.

40 It will be clear that, in the known apparatus of FIG. 1, the mode of connection of the coil D2 results in a discontinuity in the helical spring which gives rise to disturbance. To avoid such discontinuity, the rotatable frame-wound coil D2 of the embodiment of the invention shown in FIG. 2, is positioned

45 within the helical spring, one turn of the spring is rigidly connected at two oppositely disposed points 1 and 2 to the two sides of the coil D2 which are parallel to the axis of rotation of the coil. The connection of the coil to the spring is effected by adhesive attachment and must be as rigid as possible to insure that the frame-wound coil is reliably driven by the vibrating spring turn. Accordingly, adhesives of an elastic nature should be avoided, and hard, nonelastic adhesives should be used. The magnet system M2 (not shown in FIG. 2) is arranged so that the spring, that is to say the part thereof surrounding the frame-wound coil D2, is also disposed in the air gap between the poles PN2, PS2.

If the inwardly deformed portions of the spring turn, as illustrated in FIG. 2, are indented inwardly into contact with the two frame sides, the alternative embodiment illustrated in FIG. 3 may be used. In FIG. 3 the spring turn is deformed inwardly at two oppositely disposed positions, but instead of inserting the frame-wound coil D2 within the spring as in FIG. 2, the frame is applied over the spring turn so that the frame is practically suspended on the spring turn. Similar to the arrangement in FIG. 2, in FIG. 3 the frame-wound coil D2 is attached to the spring turn at points 1 and 2 by means of rigid adhesive.

70 Where a particularly high sensitivity is required and less importance is attached to the transmission of high frequencies, it is advisable to connect the frame-wound coil to more than one turn, for example with two spring turns, as shown in diagrammatic form in FIG. 4. In FIG. 4, the frame-wound coil D2 is adhesively attached to two adjacent turns of the spring at the four points 3, 4, 5 and 6.

It is preferable if each of the deformed turns is notched or provided with reduced portions to insure that the stiffness of each deformed turn plus the frame attached to it is equal to the stiffness of the undeformed turns of the spring.

The question as to whether the frame is secured in accordance with FIG. 2 or FIG. 3 is of no consequence for the end result. The choice of either of the two constructions for an individual case will therefore depend only on manufacturing considerations.

In addition to providing the advantages already described, each embodiment of the invention offers the further advantage of preventing any tensile forces of the spring from acting upon the frame and deformation thereof is therefore obviated. Accordingly, a construction of lighter weight may be adopted.

In the description hereinabove, the invention has been described only in relation to an electromechanical transducer having a rotatable frame-wound coil because, in addition to a high degree of efficiency, this construction provides for precise and controllable conditions. The apparatus responds only to torsional vibrations, proportionally to the homogeneity of the magnetic field and can also fundamentally employ electromechanical transducers which are provided with movable elements such as moving iron elements, moving magnets or the like.

What is claimed is:

1. Electromechanical apparatus for producing artificial reverberation, comprising an elongated helical spring which operates as a delay element, and electromechanical transducers for applying mechanical vibrations to the spring and for picking up the vibrations transmitted by the spring, at least one of said transducers comprising a movable element being rigidly connected to at least one turn of said helical spring at a position intermediate the ends of the spring and without any interruption in the continuity of said spring at the connection for coupling said transducer to said spring, said movable element of said transducer coupled to said spring intermediate the ends thereof being a rotatable frame-wound coil, the con-

nection between at least one turn of said spring and said rotatable frame-wound coil being made directly to a side of the frame-wound coil which is disposed in parallel relationship to the axis of rotation of said coil.

5. Electromechanical apparatus, as set forth in claim 1, wherein a hard, nonelastic adhesive being used for connecting said frame-wound coil to the turn of said spring.

3. Apparatus, as set forth in claim 1, wherein said frame-wound coil being disposed within the turn of said spring to 10 which it is connected.

4. Electromechanical apparatus, as set forth in claim 1, wherein said frame-wound coil being disposed outside the turn of said spring to which it is connected.

5. Electromechanical apparatus for producing artificial 15 reverberation, comprising an elongated helical spring which operates as a delay element, and electromechanical transducers for applying mechanical vibrations to the spring and for picking up the vibrations transmitted by the spring, at least one of said transducers comprising a movable element being 20 rigidly connected to at least one turn of said helical spring at a position intermediate the ends of the spring and without any interruption in the continuity of said spring at the connection for coupling said transducer to said spring, said movable element of said transducer coupled to said spring intermediate 25 the ends thereof being a rotatable frame-wound coil, the portion of each turn of said spring connected to said rotatable frame-wound coil being deformed inwardly whereby the polar 30 moment of inertia of each said deformed turn plus said rotatable frame-wound coil connected thereto is at least approximately equal to the polar moment of inertia of the remaining undeformed turns of said spring.

6. Electromechanical apparatus, as set forth in claim 5 wherein each inwardly deformed turn of said spring being provided with reduced portions so that the stiffness of each said 35 deformed turn plus said frame-wound coil connected thereto is equal to the stiffness of the remaining undeformed turns of said spring.
